TAPE PUNCHING MACHINE

Raymond L. Westerfield, 2045 High St., Topeka, Kans.
Filed May 21, 1962, Ser. No. 196,277
8 Claims. (Cl. 83—560)

This invention relates to new and useful improvements in machines for punching tapes for use in animated electrical advertising signs, the general operation being that as said tape is caused to travel between electrical brushes, said brushes will make contact through patterns of openings punched in the tape to cause illumination of electric lamps in a corresponding pattern in a remote bank of electric lamps, whereby to form a display sign.

The principal object of the present invention is the provision of a tape punching machine of the character described having novel means providing for a high degree of accuracy in the placement of the punched openings in the tape, since in devices of this type the precise location of the openings relative to the brushes or other circuit completing devices is highly critical.

Another object of the present invention is the provision of a tape punching machine of the character described wherein a master tape with punched openings or markings is used as a general visual guide for correctly placing the punched openings in the sign tape to be punched, but wherein the precise placement of the punched openings is governed and controlled with mechanical precision by the machine itself, whereby to eliminate human error in aligning the openings. Also, although the master tape serves as a general visual guide, no portion of the actual guide mechanism of the machine ever actually contacts said master tape. This eliminates wear and deterioration of the master tape, and provides longer life for the machine.

Other objects are simplicity and economy of construction, efficiency and dependability of operation, and general adaptability for usage wherever accurate relative location of punched openings in sheet material may be desired.

With these objects in view, as well as other objects which will appear in the course of the specification, reference will be had to the drawing, wherein:

FIG. 1 is a top plan view of a tape punching machine embodying the present invention.

FIG. 2 is a sectional view taken on line II—II of FIG. 1.

FIG. 3 is a sectional view taken on line III—III of FIG. 1.

FIG. 4 is an enlarged, fragmentary sectional view taken on line IV—IV of FIG. 2, with parts left in elevation, and

FIG. 5 is an enlarged, fragmentary sectional view taken on line V—V of FIG. 1, with parts left in elevation.

Like reference numerals apply to similar parts throughout the several views, and the numeral 2 applies to a base or frame of box-like form open at the top, said base having a series of upwardly projecting posts 4 along its upper edges which support a horizontal planar platform 6 at their upper ends. Said platform overlies the base, except that the side edges thereof terminate inwardly from the side walls of base 2, as shown.

At the left side of the base, as viewed in FIG. 1, a horizontal shaft 8 is disposed outwardly from the contiguous side of platform 6, being rotatably mounted in bearings 10 carried by base 2, and being manually rotatable by means of knob 12 affixed to the forward end thereof. Mounted on said shaft are a pair of guide spools 14 and 16. Spool 14 is disposed adjacent the front of the base, and is freely rotatable on the shaft. Spool 16 is disposed adjacent the back of the base, and is fixed

2

on the shaft. Similarly, a second horizontal shaft 18 is disposed adjacent the right side of the base as viewed in FIG. 1, parallel to shaft 8. Shaft 18 is supported rotatably in bearings 20 affixed to the base, is manually rotatable by means of a knob 22 affixed to the forward end thereof, and has a pair of guide spools 24 and 26. Spool 24 is disposed adjacent the front of the base in alignment with spool 14, and is fixed on the shaft. Spool 26 is disposed adjacent the back of the base in alignment with spool 16, and is freely rotatable on the shaft.

Trained about guide spools 14 and 24 is an endless master tape 28 of pliable material, the upper reach of said tape resting slidably on the top surface of platform 6, and its lower reach being disposed in base 2 below the platform. Said tape carries a series of letters 30 (as shown) or numerals or other desired characters, each character being formed by a series of circular marks imprinted on the tape in the desired pattern. It will be noted that the marks forming the characters are arranged in regular rows, both longitudinally and transversely of the tape. In the particular master tape shown, the transverse rows of marks are inclined angularly to the longitudinal extent of the tape, but this is optional.

The master tape, depending on the number of characters it may carry, may be longer than can be supported directly by spools 14 and 24. To support this extra length, and to maintain the tape reasonably taut, the lower reach of the tape may be trained about a plurality of idler rollers 32 supported rotatably by brackets 34 depending from platform 6. Tape 28 may be advanced in either direction by turning spool 24 by means of knob 22. In order to assure good traction between the tape and spool 24, a pressure roller 36 urges said tape against the spool. Said pressure roller is carried rotatably by a crank 38 pivoted in a post 40 fixed to base 2, and is urged against the tape by a spring 42. Turning knob 12 will not affect tape 28, since shaft 8 turns freely in spool 14.

The sign tape 44, or the tape to be punched, is fed from a roll 46 supported rotatably in base 2 by a bracket 48 depending from platform 6. From said roll, tape 44 is trained about spool 26, passes over the upper surface of platform 6 in parallel relation to master tape 28, and is then passed around spool 16 and out of the machine. Tape 44 is advanced by turning spool 16 by means of knob 12, and to insure good traction between the spool and tape, a pressure roller 50 presses said tape firmly against the spool. Said pressure roller is supported rotatably by a crank 52 pivoted in a post 54 affixed to base 2, and is urged against the tape by a spring 56. Turning knob 22 will not affect tape 44, since shaft 18 turns freely in spool 26. Since accurate punching of tape 44 as it passes over platform 6 depends in part on accurate spacing of the punches from the edges of the tape, and since as will presently appear this edge spacing would be inaccurate if the tape were permitted to move laterally relative to its direction of travel, a pair of guides 58 are fixed adjustably to the top of platform 6 by means of screws 60 (see FIG. 1). The tape passes between these guides, and is thereby accurately held in its line of travel. The sign tape is of course usually formed of electrical insulating material, to serve its purpose in the sign mechanism in which it is eventually employed.

The actual punch mechanism is carried on the top surface of platform 6 intermediate the sides thereof. This mechanism includes a guideway 62 supported on platform 6 by a bracket 64, and in which a head 66 is supported for horizontal sliding movement parallel to the direction of movement of tapes 28 and 44. Said head is moved manually by means of a lever 68 pivoted to platform 6 at

70, and a link 72 pivotally connected to lever 68 at 74 and to head 66 at 76. For reasons which will presently be discussed, it is desirable that means be provided for moving head 66 accurately in steps corresponding to the spacing between the transverse rows of marks forming characters 30 on master tape 28, measured longitudinally of this tape. For this purpose, there is provided a detent mechanism best shown in FIG. 4 and comprising a detent ball 78 retained by guideway 62 and engageable successively in a series of sockets 80 formed in head 66, as said head is moved in the guideway. Said detent ball is biased toward said sockets by a spring 82 adjustably tensioned by a screw 84 threaded in the guideway. The detent will of course yield to permit movement of the head by lever 68, but nevertheless serves as a means for positioning the head very accurately at any of a series of predetermined positions.

Affixed to the top of head 66 is a guideway 86 in which is slidably mounted a bar 88 which is disposed horizontally and parallel to the angle of inclination of the transverse rows of marks forming the characters 30 on the master tape. Said bar slides longitudinally in guideway 86, and extends both forwardly and rearwardly therefrom, whereby to overlap tapes 28 and 44 respectively. For reasons which will presently be discussed, it is desirable that means be provided for moving bar 88 accurately in steps corresponding to the spacing between the longitudinal rows of the marks forming characters 30 on the master tape, measured transversely of the tape. For this purpose, there is provided a detent mechanism best shown in FIG. 4 and comprising a detent ball 90 retained in guideway 86 and engageable successively in a series of sockets 92 formed in bar 88, as said bar is moved in said guideway. Said detent ball is biased toward said sockets by a spring 94 adjustably tensioned by a screw 96 threaded in the guideway. The bar is moved manually by an upright lever 98 pivoted at its lower end, as at 100, to a bracket 102 affixed to guideway 86, and a link 104 pivoted at one end to said lever at 106, and pivoted at its opposite end, as at 108, to a standard 110 which is affixed to the rearward end of bar 88. Detent 90 will of course yield to permit movement of the bar by lever 98, but nevertheless serves as a means for positioning the bar very accurately at any of a series of predetermined positions.

Affixed in the forward end of bar 88 by set screw 112 is a depending stylus or pointer 114, the lower end of which is disposed closely adjacent, but out of contact with, master tape 28. Rigidly affixed to the rearward end of bar 88, directly above sign tape 44, is a block 116 in which is slidably mounted for vertical movement a punch die 118. Affixed to the lower side of said block are a pair of horizontal bars 120 and 122 which define a horizontal slit 124 therebetween, as best shown in FIG. 5. Sign tape 44 is trained through said slit. Upper bar 120 has a hole 126 formed therethrough which acts as a guide for die 118. Lower bar 122 acts as a ledger plate for the die, and has a hole 128 therein for receiving the die after it has pierced the tape.

Die 118 extends above block 116, and is connected at its upper end by pivoted link 130 to the central portion of a lever 132. One end of said lever is pivoted at 134 to an upstanding post 136 affixed to block 116, and the other end of the lever is pivoted at 138 to the upper end of a solenoid armature 140. The coil 142 is rigidly mounted on block 116, so that whenever said coil is energized, armature 140 will be pulled downwardly, and will act through lever 132 to force die 118 downwardly to pierce tape 44 in slit 124. The die is normally biased to an upwardly retracted position by a compression spring 144 disposed about said die and urging it upwardly. As shown diagrammatically in FIG. 2, solenoid coil 142 is connected by wires 146 and 148 to electric line wires 150 and 152 through a pushbutton electric switch 154 which, for convenience, is mounted at the upper end of

lever 98, so that said coil is energized whenever said pushbutton switch is closed.

In order to assist in accurate placement of the punched openings in tape 44, a horizontal guide plate 156 is attached to upper die plate 120 and extends therefrom in the direction of travel of tape 44 therefrom as best shown in FIG. 1, so as to overlie the upper surface of said tape. Said guide plate has two rows 158 and 160 of punched openings formed therein, said rows extending parallel to bar 88. Row 158 is spaced from die 118, in the direction of tape travel, a distance equal to the desired spacing between letters of the message to be punched in the tape and row 160 is spaced from the die a distance equal to the desired spacing between words of the message.

In use, master tape 28 is first moved by turning knob 22 until the leftmost transverse row of marks forming the desired character on the tape is disposed beneath stylus 114. Then by manipulation of lever 98 the stylus may be positioned successively over each mark in that transverse row of marks. At each position, push button 154 is depressed to actuate the die 118 to punch a hole in tape 44. When that transverse row of holes has been completed, lever 68 is manipulated to move head 66 to the right to position stylus 114 over the next transverse row of marks in the desired character on tape 28, and by manipulating lever 98 the stylus is positioned over each mark in that row, pressing push button 154 at each position. This is repeated until all the marks in the entire character have been duplicated by punched openings in tape 44. During this entire process neither of the tapes are moved. Furthermore, stylus 114 acts only as a rough guide, the final and accurate positioning of the die at each position being accomplished by detent balls 78 and 90. This eliminates all human error and inaccuracies in the relative positoning of the holes representing each single letter or character, and is extremely important in that inaccuracy in this respect is very detrimental to the efficient operation of the tape in the sign mechanism for which it is intended. After a letter or character is completed as described above, head 66 is moved to the left by lever 68, tape 44 is advanced to the left by turning knob 12 until the last-punched transverse row of holes in said tape is disposed directly beneath the row 158 of holes in guide plate 156, tape 28 is advanced in either direction by turning knob 22 until the leftmost row of transverse marks in the next desired character on tape 28 is disposed beneath stylus 114, and the process repeated for the new letter or other character. When an entire word is completed, the resetting of the tapes as previously described in this paragraph is repeated, except that in advancing tape 44 the last transverse row of holes in that tape is positioned beneath row 160 of holes in guide plate 156. This provides the desired spacing between words in the sign tape. The described visual procedure for resetting tape 44 to provide proper spacing between letters and words does admit some slight error in these spacings, as compared to the virtually absolute accuracy of spacing within single characters, but this is not considered detrimental in the finished tape. Also, the stylus does not ride on or even contact the master tape at any time. This prevents wear and tear on the master tape which commonly occurs, for example, when a stylus must actually engage in punched openings in a master tape.

While I have shown and described a specific embodiment of my invention, it will be readily apparent that many minor changes of structure and operation could be made without departing from the spirit of the invention as defined by the scope of the appended claims.

What I claim as new and desire to protect by Letters Patent is:

1. A tape punching machine comprising:
- (a) a base,

- (b) a master tape carried by said base, and having characters imprinted thereon,
- (c) a sign tape carried by said base,
- (d) means for moving said tapes independently in parallel relation,
- (e) a bar carried by said base above said tapes and being movable relative to said base both longitudinally and transversely relative to said tapes,
- (f) a stylus carried by said bar adjacent said master tape and adapted to be moved in tracing relation to the characters imprinted thereon,
- (g) a punch die carried by said bar in the same relation to said sign tape as said stylus bears to said master tape, and being operable when actuated to punch a hole in said sign tape, and
- (h) means for actuating said punch die.

2. A tape punching machine as recited in claim 1 with the addition of:

- (a) means for releasably securing said bar selectively at any of a series of accurately spaced points in its movement longitudinally of said tapes, and
- (b) means for releasably securing said bar selectively at any of a series of accurately spaced points in its movement transversely of said tapes.

3. A tape punching machine as recited in claim 1 wherein each of the characters imprinted on said master tape are defined by a series of marks arranged in regularly spaced rows extending both longitudinally and transversely of said tape, and with the addition of:

- (a) means for releasably securing said bar selectively at any of a series of accurately spaced points in its movement longitudinally of said tapes, the spacing of said points corresponding to the spacing between said transverse rows of marks on said master tape, and
- (b) means for releasably securing said bar selectively at any of a series of accurately spaced points in its movement transversely of said tapes, the spacing between said points corresponding to the spacing between said longitudinal rows of marks on said master tape.

4. A tape punching machine comprising:

- (a) a base,
- (b) a master tape carried by said base, and having characters imprinted thereon,
- (c) a sign tape carried by said base,
- (d) means for moving said tapes independently in parallel relation,
- (e) a head carried by said base for movement longitudinally of said tapes,
- (f) means for moving said head,
- (g) a bar carried by said head for movement transversely of said tapes,
- (h) means for moving said bar,
- (i) a stylus carried by said bar adjacent said master

tape and adapted by movement of said head and said bar to move in tracing relation to the characters imprinted thereon, and

- (j) a punch die carried by said bar in the same relation to said sign tape as said stylus bears to said master tape, and operable to punch holes in said sign tape.

5. A tape punching machine as recited in claim 4 wherein each of the characters imprinted on said master tape are defined by a series of marks arranged in regularly spaced rows extending both longitudinally and transversely of said tape, and with the addition of:

- (a) means for releasably indexing said head at any of a series of points in its movement longitudinally of said tapes, the spacing between said points corresponding to the spacing between said transverse rows of marks on said master tape, and

- (b) means for releasably indexing said bar at any of a series of points in its movement transversely to said tapes, the spacing between said points corresponding to the spacing between said longitudinal rows of marks on said master tape.

6. A tape punching machine as recited in claim 5 wherein said indexing means comprise spring loaded detents.

7. A tape punching machine as recited in claim 5 wherein said means for moving said bar includes a manually operable lever, and wherein said punch die is provided with electrical operating means including an electric switch mounted on said lever.

8. A tape punching machine as recited in claim 5 with the addition of:

- (a) a guide plate carried by said bar adjacent said punch die and overlying said sign tape, said guide plate having a plurality of rows of holes formed therethrough, said rows extending parallel to the direction of movement of said bar transversely to said tapes, and being spaced from said punch die, in a direction longitudinal of said tapes, at distances corresponding to various spacings between characters which may be desired in the sign tape.
